UNITED STATES PATENT OFFICE.

CHRISTIAN FUSKERUD, OF WENTWORTH, SOUTH DAKOTA.

APPAREL-HANGER.

1,034,439.

Specification of Letters Patent.

Patented Aug. 6, 1912.

Application filed January 23, 1912. Serial No. 672,892.

To all whom it may concern:

Be it known that I, CHRISTIAN FUSKERUD, citizen of the United States, residing at Wentworth, in the county of Lake and State 5 of South Dakota, have invented certain new and useful Improvements in Apparel-Hangers, of which the following is a specification.

This invention relates to improvements in apparel hangers.

10 The primary object of my invention is to provide a light, neat, inexpensive garment hanger to give support to a plurality of articles of apparel.

Another object is to provide an inexpensive apparel hanger, made of wire, especially constructed to receive such articles of apparel as are usually discarded upon entering a room.

Another object is to provide an apparel 20 hanger so arranged that the same may be packed in a neat, compact package.

With these and other objects in view the present invention consists in the combination and arrangement of parts as will be 25 hereinafter more fully described and finally pointed out in the appended claims, it being further understood that changes in the specific structure shown and described may be made within the scope of the claims without departing from the spirit of the invention.

In the accompanying drawings forming a part of this specification, and in which like numerals of reference indicate similar parts in the several views:—Figure 1 shows a side 35 view of an apparel hanger constructed according to my invention, while Fig. 2 shows a front view of my apparel hanger disclosing the same as giving support to a pair of gloves, a hat, and a coat.

40 The aim of my invention is to provide a garment hanger arranged to be secured to the wall, to receive such articles of apparel as are usually discarded upon entering a room, such as a hat, gloves, top coat, shawl, cane or an umbrella.

In carrying out the object of my invention, I employ two similar supporting members each comprising a threaded stem 5, having a spring coil 6, ending in a recurved 50 clasping arm 7, as clearly disclosed in Fig. 1. Two such supporting stems are employed, each receiving one end of a V-shaped hanger made of wire and comprising the straight bar sections 1, each ending in a terminal eye 4, the lower end of this V-shaped hanger ending in a recurved hook 3.

The sections 1 are extended in parallel and are united as is shown at 2, so that the supporting hook 3 is of double thickness as shown in Fig. 2.

Held to each supporting stem 5 is a hanger bar 9, two such bars being employed as shown, each bar ending in a terminal eye 8, held upon a supporting stem, while the opposite end 10 of each hanger bar is bent 65 at right angles, and ends in an eye 12.

Pivotal held within the terminal eyes 12, is a hat supporting bar 14, having a centrally disposed half loop 15, curved downward, this bar 14 ending in terminal 70 eyes 13, in engagement with the eyes 12. As shown in Fig. 1, this hat receiving loop 15, is held outward a suitable distance from the hanger bars 1.

The hanger is secured in placing the 75 threaded stems through the terminal eyes 4 and 8, and then screwing these supporting stems into the wall. In this instance, the spring coils 6 serve as a stop in forcing and holding the members 1 and 9 together, as 80 shown in Fig. 1. In this condition, the upper recurved end of each stem rests under tension against the wall, giving support to the same.

The clasping arms 7 serve to receive 85 gloves, newspapers, books and the like, which are placed behind the spring arms, while the hook 3 receives such garments, as an overcoat. A hat is secured in carrying the loop 15 outward and resting the crown 90 within the loop and then allowing the loop 15 to find its perpendicular. An umbrella, cane or the like, is given support upon the bar portions 10.

A garment hanger constructed according 95 to my invention is extremely simple and inexpensive in construction, and both durable and efficient in operation, and the articles of apparel can be instantly removed or replaced.

In referring to Fig. 1, it will be noted that the hangers 9 are diagonally held for the reason that the length of the bar 14 is much greater than the distance between the ends 4 of the V-shaped hanger.

Having thus described my said invention, what I claim as new and desire to secure by United States Letters Patent, is:—

1. An apparel support comprising two similar supporting stems, each having a 110 spring coil ending in a clasping arm, a V-shaped hanger having terminal eyes upon

said stems, and ending in a hook, two diagonally held hanger bars, each having one end bent at right angles, both ends of each bar ending in a terminal eye, one eye of each bar in engagement with a stem, and a supporting bar having a centrally disposed half loop, and terminal eyes, engaging the bent ends of said hanger bars.

2. An apparel support comprising two similar threaded supporting stems, each having a spring coil ending in a clasping arm, a V-shaped hanger having terminal eyes upon said stems, and ending in a hook, two diagonally held supporting bars, each having one end bent at right angles, both ends of

each bar ending in an eye, one eye of each bar in engagement with a threaded stem and a supporting bar having a centrally disposed hat receiving half loop, and terminal eyes engaging said bent ends, the length of 20 said supporting bar being greater than the distance between the ends of said V-shaped hanger.

In testimony whereof I affix my signature in presence of two witnesses.

CHRISTIAN FUSKERUD.
